UNITED STATES PATENT OFFICE.

WILLIAM H. ARMSTRONG, OF PLAINFIELD, NEW JERSEY, ASSIGNOR TO INGERSOLL-RAND COMPANY, OF JERSEY CITY, NEW JERSEY, A CORPORATION OF NEW JERSEY.

MECHANICAL TIE TAMPER.

Application filed November 19, 1925. Serial No. 69,951.

To all whom it may concern:

Be it known that I, WILLIAM H. ARMSTRONG, a citizen of the United States, and a resident of Plainfield, Union County, and State of New Jersey, have invented a certain 5 Mechanical Tie Tamper, of which the following is a specification accompanied by drawings.

This invention relates to tie tampers and 10 more particularly to a form of tie tamper adapted to be operated manually.

An object of this invention is to apply greater power for tamping railroad ties and to enable the operator to conveniently apply 15 such power. Other objects and advantages of the invention will be in part obvious and in part pointed out hereinafter.

The drawing illustrates one form which the invention may assume in practice and is 20 a perspective view of a tie tamper mounted on a railroad tie illustrating the manner in which the device operates.

Referring to the drawing, the tie tamper includes a shoe A having a flat upper portion 25 terminating in downwardly projecting side portions B spaced apart at approximately the standard width of a tie. The downwardly projecting portions B and C may be provided with teeth D to grip the tie and prevent the shoe A from slipping easily 30 thereon. At either side of the shoe A a pair of upright bearing members E and F are preferably formed integrally with the shoe A and adapted to support a pair of curved 35 tamper bars G and H provided with broadened ends J adapted to push the rock or other ballast material under a tie K. The tamper bar G is supported on the upright bearing member E by means of a link L and a bell 40 crank O pivoted to the bar G by means of pins P and Q. Similarly the tamper bar H is supported on the upright bearing member F by means of a link R and a bell crank S being pivoted to the bar H by the pins T and 45 U respectively. The link L is provided with a pivotal connection V at the bearing member E. Similarly the link R is pivoted to the bearing member F by means of a pivot W. Pivots X and Y support the bell cranks O 50 and S respectively on the bearing members E and F respectively. The link L and bell crank O may be parallel to each other and the link R and bell crank S likewise, so as to provide a parallel movement to the tamper 55 bars G and H. Furthermore by reason of

the link connections thus provided by the tamping bars G and H move toward each other as they descend.

The bell cranks O and S are connected to raise and lower the tamping bars G and H 60 by means of a lever Z preferably manually operated, connected to the bell cranks O and S by means of links b and c respectively in such a manner that as the lever Z is pushed to one side the bell cranks O and S push the 65 tamper rods G and H downwardly and toward each other under the tie K. As the lever Z is pushed in the opposite direction the tamper rods G and H are raised and swung outwardly from under the tie K. 70 Preferably the lever Z is pivoted on bearing members d by means of a pin e. The bearing members d may be formed integral with the shoe A.

To operate the tamping device the lever Z 75 is swung to the position shown in dotted lines Z' whereat the tamper bars G and H are swung to the positions G' and H' respectively. The other movable members being in corresponding positions, the shoe A 80 is placed over the tie K so that the downwardly extending portions B and C may grip the sides of the tie K. With suitable ballast material adjacent the bottom of the tie K the lever Z is pulled longitudinally 85 to the left forcing the tamper bars G and H downwardly and inwardly to drive the ballast material under the tie K. Thereafter the lever Z is swung back to the position Z' and more ballast material is placed in front 90 of the broadened ends J of the tamper bars G and H to be forced under the tie K upon movement of the lever to the left.

I claim:

1. Tamping apparatus comprising a pair 95 of tamping bars adapted to be placed on opposite sides of a tie, a single lever, and means operatively connecting said lever with said tamper bars to force said bars downwardly and toward each other under the tie. 100

2. Tamping apparatus comprising a pair of tamping bars adapted to be placed on opposite sides of the tie, a lever, a shoe adapted to be placed over the tie to support 105 said tamping bars and said lever, and means operatively connecting said lever with said tamper bars to force said bars upwardly and toward each other under the tie.

3. Tamping apparatus comprising a pair 110 of tamper bars adapted to be placed at

opposite sides of a tie, a lateral swinging lever, a shoe adapted to be placed on said tie to pivotally support said lever and said tamper bars, and means operatively connecting said lever with said tamper bars to force said bars downwardly and toward each other under the tie.

4. Tamping apparatus comprising a pair of tamper bars adapted to be placed on opposite sides of a tie, a laterally swinging lever, a shoe to support said tamper bars and said lever provided with a flat portion to rest on the top of said tie, and a pair of downwardly extending portions to grip the sides of said tie, and means for operatively connecting said lever and said tamper bars to force said tamping bars downwardly and toward each other under said tie.

5. Tamping apparatus comprising a pair of tamper bars adapted to be placed at opposite sides of a tie, a shoe adapted to fit over said tie, bearing members extending from said shoe, links and bell cranks connecting

said bearing members with said tamper bars, and a lever pivotally mounted on said shoe and connected with said bell cranks to force said tamper bars downwardly and toward each other under said tie. 25

6. Tamping apparatus comprising a pair of tamping bars adapted to be placed at opposite sides of a tie and having broadened ends to contact with ballast material, a shoe adapted to fit over and grip said tie, bearing members extending upwardly from said shoe, links and bell cranks pivotally mounted on said bearing members and pivotally connected with said tamping bars, a laterally swinging lever pivotally mounted on said shoe between said bearing members and links connecting said lever with said bell cranks whereby said tamper bars are forced downwardly and toward each other under said tie by lateral movement of said lever. 30 35 40

In testimony whereof I have signed this specification.

WILLIAM H. ARMSTRONG.
